CLAIM

The ornamental design for shadow box, as shown and described.

DESCRIPTION

FIG. 1 is a front elevational view of the shadow box showing my new design, with the hinges and door closure clasp shown in broken lines. The broken line showing of the hinges and door closure clasp is for illustrative purposes only and forms no part of the claimed design;

FIG. 2 is a rear elevational view thereof;

FIG. 3 is a left elevational thereof;

FIG. 4 is a right elevational view thereof;

FIG. 5 is a top plan view thereof; and,

FIG. 6 is a bottom plan view thereof.
